UNITED STATES PATENT OFFICE.

JAMES W. KIRBY, OF HARLAN, IOWA.

STOCK WATERER.

Application filed September 13, 1926. Serial No. 135,181.

The invention relates to means for supplying water to stock for drinking purposes and has as one of its objects to maintain a predetermined level of the water and prevent its freezing in cold weather.

A further purpose of the invention is to prevent the fouling of the water and to guard against the animals having access thereto except for drinking.

The invention contemplates a stock waterer embodying two shells, one within the other, the inner shell constituting a receptacle for receiving and holding the water and the outer shell forming a casing to receive the heater and provide a space for the circulation of the warm air.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof reference is to be had to the following description and the drawings hereto attached, in which,—

Figure 1 is a horizontal sectional view of a stock waterer embodying the invention taken on the line 1—1 of Figure 3.

Figure 2 is a vertical sectional view on the line 2—2 of Figure 1.

Figure 3 is a sectional view similar to Figure 2, taken on the line 3—3 of Figure 1.

Figure 4 is a fragmentary view showing more clearly the offset portion of the water chamber beneath which the heater is placed for direct action, and

Figure 5 is a fragmentary sectional view on the line 5—5 of Figure 1, looking in the direction of the arrows.

Corresponding and like parts are referred to in the following description and designated in the several views of the drawings by like reference characters.

The stock waterer comprises an inner shell 1 and an outer shell 2, a space being formed between the two shells for circulation of warm air to prevent freezing of the water in cold weather. The outer shell 2 is in the nature of a casing and is of rectangular outline and stepped upon its top to provide surfaces in different planes, the upper surface constituting a removable cover 3, and the

lower surface a fixed top 4, in which openings 5 are formed for the reception of pails 6, or like vessels. The pails or vessels 6 are removable and each has an opening in its bottom, which is controlled by means of a valve 7. The inner shell 1 is fixed and is substantially of L-form, as shown most clearly in Figure 1. The inner shell constitutes a water chamber and the portion closed by the top 4 receives the pails or vessels 6. A float 8 is arranged in the other portion of the chamber and controls a valve 9 which admits water into the chamber. A pipe 10 connects with the bottom of the water chamber and leads to a suitable source of supply, not shown. That portion of the water chamber receiving the float 8 extends flush with the top of the casing which is closed by means of the cover 3 to provide ample movement for the float 8. An offset portion 11 projects laterally from the rear walls of the water chamber and is located in the angular space formed between the two portions. This offset portion 11 is located at the top of the water chamber, as shown most clearly in Figure 3 and extends to the top portion of the casing closed by means of the cover 3. A suitable heater 12, such as a lamp is disposed beneath the offset portion 11 so that the latter may receive direct action of the heat, and thereby prevent the congealing of the water at the surface in extreme cold weather. The warm air from the heater circulates about the water chamber through the space formed between said chamber and the walls of the casing, as indicated most clearly in Figure 1.

The cover 3 has an opening 13 opposite the offset portion 11 for the escape of any vapor that may be formed. An opening 14 is formed in the rear wall of the casing 2 and the same is protected by means of a hood 15 which is open at the bottom and closed at its top and sides.

The casing 2 may be closed by a bottom if preferred, or may be closed by the ground or platform upon which the waterer may be placed. When the water is turned on the float valve 9 controls the supply to the water chamber. The water passes from the chamber into the drinking vessels 6 through the valve controlled opening in the bottom thereof, and as the level of the water lowers in either one of the vessels 6 water flows from the chamber into said vessel to preserve and maintain a uniform level in the

vessel 6 and the water chamber, as will be readily understood. The cover 3 admits of the heater or lamp 12 being placed in position or removed for cleaning or replenishing.

Having thus described the invention, I claim:

1. A stock waterer comprising a casing of rectangular outline, an L-shaped water chamber disposed within the casing to provide a surrounding space, said water chamber having an offset portion at its top overhanging the space of the casing, one portion of the water chamber being closed by a top in which openings are formed for the reception of drinking vessels, a float controlled valve arranged within the other portion of the water chamber for regulating the supply of water thereto, a heater within the casing disposed beneath the offset portion of the water chamber, and a removable cover closing the portion of the casing containing the said offset portion of the water chamber and the part thereof containing the float valve.

2. A stock waterer comprising a casing 25 having a stepped top, an L-shaped water chamber disposed within the casing to leave a surrounding space for the circulation of warm air, a top closing the lower stepped portion and extending over a part of the 30 water chamber and having openings therein for the reception of drinking vessels, a float controlled valve in the other portion of the water chamber, an offset portion in the angular space formed between the parts comprising the water chamber and located at the top thereof, a heater within the casing disposed beneath the offset portion of the water chamber, a cover closing the upper 35 stepped portion of the casing and the part of the water chamber in which the float valve is located and extending over and closing the top of the said lateral offset portion, the casing having an opening in a wall which is protected by a hood. 40

45 In testimony whereof I affix my signature.

JAMES W. KIRBY. [L. S.]
